UNITED STATES PATENT OFFICE.

JULES LEMERY, OF DIEPPE, FRANCE.

EXTENSIBLE FRAME.

Application filed February 12, 1923. Serial No. 618,705.

To all whom it may concern:

Be it known that I, JULES LEMERY, a citizen of the Republic of France, and residing at Dieppe, Seine Inferieure Department, 5 No. 34, Rue du Général Chanzy, in the Republic of France, have invented certain new and useful Extensible Frames, of which the following is a specification.

The present invention refers to an extensible frame which is principally intended to allow the painters to show to their purchasers their paintings or pictures of different sizes suitably framed, without the necessity for them to incur the expenses or 10 have the trouble of a large number of frames. The same can also be arranged so as to serve as an extensible framing to be used for maintaining in a stretched state the canvas to be painted upon.

20 This extensible frame is composed of members or parts sliding the one above the other and of a small number of intermediate members which are used for filling up the empty spaces of variable length which are 15 left between the ends of the sliding members or parts.

The accompanying drawing shows by way of example several forms of construction of a frame made according to the invention.

Fig. 1 is a front view of this frame, certain intermediate parts being in position while some others have been removed.

Fig. 2 is a rear view thereof.

35 Fig. 3 is a section of same made according to line A—A of Fig. 1.

Fig. 4 is an elevation of a second form of construction of the frame, certain parts or members being broken away or removed.

40 Fig. 5 is an elevation of a third form of construction the intermediate parts being removed.

Fig. 6 is a cross section made, on a larger scale, according to line B—B of Fig. 5.

45 Fig. 7 is an elevation of a fourth form of frame, adapted to be used as a framing for stretching the canvas which is to be painted upon.

Fig. 8 is a cross section made according to line C—C on Fig. 7.

Each one of the four sections of the frame shown in Figures 1 to 3 comprises a rear member 1 which can be plain or ornamented and which is connected at right-angle with 55 a front member 2.

This connection is made in any rigid

manner for instance by means of screws 3 or simply by means of glue, etc.

Each rear element on one side of the frame is rigidly secured to the front element of one of the adjacent sides of the frame. The rear element of each side of the frame is slideable upon the front element of the same side of the frame.

The members 1 and 2 are suitably grooved so that they may be able to slide longitudinally the one with reference to the other, the member 1 comprising a groove 4 in which enters a corresponding tongue 5 of the member 2.

These grooves and tongues can be dovetailed so that the members can be tightly maintained the one against the other. Furthermore, the guiding can be obtained if necessary by means of slides made of 75 metal or lined with metal in order to secure a greater strength and an easier sliding, if deemed necessary.

Moreover, each member 1 comprises a longitudinal mortise 6 in which slides a bolt 7 secured to the corresponding member 2; nuts 8 allow to maintain the parts well pressed the one against the other in every one of the positions in which they have been placed.

Of course, this mode of fastening has been given by way of example only, and can be replaced by any other similar one.

In order to fill the empty spaces existing between the members, I make use of intermediate members or parts such as 9 which are preferably provided with studs 10 and mortises or slots 11 so as to be perfectly connected at their ends with the members 1 which are provided with corresponding slots or mortises and studs.

Whereas there is a limited number of sizes of canvas currently used, it is only necessary to have a small number of intermediate members of different lengths in order to impart to the frame all the required sizes, as well to the height as to the width.

Fig. 1 shows the frame in front view, two intermediate members 9 being in position, the two others being removed.

Fig. 2 shows the back of the same frame. Studs 12 and slots or mortises 13 can also be provided at the ends of the members 1.

It is obvious that the members 2 and the intermediate parts 9 can be of any profile, 110 that the said members or parts can be gilt or ornamented in any suitable manner.

If necessary, the ornamentalations can be such that the joints of the members 2 and 9 will be concealed as well as possible.

In the form of construction which is shewn in the drawings, the members 2 and 9 are provided with a rabbet 14 into which the paintings are located.

According to Fig. 4, the frame comprises four angle-pieces 15 which are L-shaped and 10 the ends of which are preferably cut according to ornamental lines, for example, as shewn in the drawings so that the joints may be more easily concealed.

These parts 15 are connected through 15 straight parts 16 which are situated at the rear part of the frame and comprise grooves 17 in which enter bolts 7 connected with the parts 15, the fastening being obtained by means of nuts 8, as previously set forth.

20 Intermediate members 9, bordered, moulded, or ornamented in the same way as the parts 15 are located between the latter so as to fill the intervals. These parts are maintained for example by means of bolts 25 7 and nuts 8, like the previous ones (which have not been represented).

Projecting ornamentalations 18 preferably cover the joints so as to entirely conceal same. These ornamentalations can be connected with the angle pieces 15 or the intermediate members, or still be independent from the one or the other.

In the arrangement shewn in Figs. 5 and 6, every angle or corner of the frame comprises a front part 19 and a back part 20 rigidly connected together and forming an angle piece, as in the previous form of construction, but instead of being mitered the ends of the part or member 19 are cut at 40 right angle with reference to the direction of the sides of the frame, as shewn in 21 and 22, which is more advantageous with reference to the perfectness of the joints and the facility of concealing the same.

45 The member 19 carries a bolt 7 which passes through a groove 6 of the part 20 belonging to the following angle of the frame, and these two parts are guided the one above the other by means of strips or 50 mouldings 23 located in the grooves 24 of the part 20 and sliding in grooves 25 of the member 19. The fastening at the required place is obtained by means of nuts 8 which are screwed upon the bolts 7. As 55 in the previous case, the empty places existing between the front parts 19 are filled by intermediate members such as 26 having the same section and the same ornamentation as the members 19.

60 In order to maintain these members in position, it may be only necessary to provide at one end of every one of them a slot or mortise 27 which applies itself upon a pro-

jection 28 fixed to the adjoining part 19, and at the opposite end, a projection 29 entering into a slot 30 of the corresponding part 19.

Of course, any other suitable fastening means can be used for the same purpose, for instance other bolts 7 and other nuts 8 similar to those which secure the parts 19 to the parts 20.

The frame shewn in Figs. 7 and 8 differ from the one which has been previously described in that the parts or members 19 and 20 have a trapezoidal cross section in order to form a slightly dished frame so that the canvas to be painted upon which will be stretched over the frame and nailed around its periphery will be solely supported by 80 the ridges 31 of the frame.

In order to avoid the yielding of the long sides of the extensible frame under the action of the tension of the canvas it may be useful to interpose between them cross-ties or stays the length of which can be adjusted; such a tie can for example consist of a threaded rod or stem 32 which freely slides in a tube 33 and which carries a nut 34 so arranged as to bear against 90 an end of this tube; the other end of the tube carries a stud 35 which enters one of the holes 36 provided in one of the members 20 while the external end of the rod 32 enters one of the holes 36 of the opposite part 20. It is only necessary to turn the nut 34 in order to modify, according to the requirements, the length of the extensible cross-tie which is thus constituted.

The rear portions of the frame adapted 100 to receive the tacks or nails for fixing the canvas are preferably made of soft wool or lined with soft wood, while the front members 19 and 26 can be made of hard wood or lined with metal so as to insure the 105 necessary rigidity and strength.

Claim:—

An extensible frame for paintings or pictures comprising L-shaped angle parts, the two arms of each angle part being placed 110 in two different front and rear planes and being rigidly fixed the one against the other, means for guiding and fixing the front arm of each angle part to the rear arm of the following angle part, and intermediate parts of different lengths adapted to 115 fill the variable empty spaces provided between the front arms of the consecutive angle parts.

In testimony that I claim the foregoing 120 as my invention, I have signed my name in presence of two subscribing witnesses.

JULES LEMERY.
